MACHINE FOR DIE CASTING UNDER
PRESSURE

Karl Lebküchner, Granichen, Switzerland, assignor to the firm Injecta Aktiengesellschaft, Teufenthal, Canton of Argovie, Switzerland

Application May 27, 1938, Serial No. 210,529
In Switzerland May 29, 1937

5 Claims. (Cl. 22—93)

The invention relates to a machine for die casting under pressure which can be arranged for automatic operation, but may also be hand operated.

5 Like all machines of this kind also the present machine comprises a hydraulically controlled piston pressing the movable half of the steel mould towards the stationary half by means of a block guided parallelly with the piston.

10 The invention consists in that said block is loosely coupled with the piston so that block and piston may be moved in relation to each other.

The coupling could be effected in a different manner. Most convenient is a hydraulic coupling which may be established or abolished at a given time. It is possible by this manner of coupling to determine the moment for executing this movement. By suitable controlling devices it will be possible to determine the term of abolishment of 20 the coupling and to influence the speed of the movement.

The annexed drawing illustrates an automatic machine according to the present invention.

Fig. 1 represents the machine with closed 25 mould just after a casting operation.

Fig. 2 shows the single members with the mould opened and cores withdrawn and

Fig. 3 shows the position of the different parts at the moment when the casting is expelled.

30 The whole arrangement is shown by top views.

The represented machine comprises a frame 1 within which are placed at one end the closing cylinder 2 with a piston 3 and different guides for the rods 4 required in such machines for 35 guiding the so called block 13. The rods 4 are held fast at the other end of the frame, where is also shown diagrammatically the crucible 5 and the pressure piston which is not represented.

Besides the closing cylinder 2 there are two 40 further cylinders 6, 6' with pistons 7, 7'. The piston rods 8, 8' carry checks 9, 9', 10, 10' and are guided in eyes 11, 11' of block 13. The checks 9, 9', 10, 10' may be dispaced on the rods and the cylinders 6, 6' are communicating with a controlled source of pressure liquid.

Piston 3 is connected to the block 13 by means 45 of a hydraulic coupling. This consists of a cylinder 12 held fast by the block and provided with a piston 14. The inside 15 of the cylinder communicates by an axial bore 16 of the piston rod with the hind portion 17 of the mould closing cylinder 2. A cut off valve 18 controls the bore 16, the purpose of which will be explained further on.

55 The useful area of the cylinder inside 15 is smaller than the useful area of the hind portion 17 of the cylinder and this latter is smaller than the useful cylinder area 19 of the fore part. Therefrom follows that with the same pressure at 15 and 17 the piston 3 will move from the

left to the right if it be supposed that the pressure at 19 be relieved by opening a drain.

The piston rod 3 carries behind cylinder 12 rings 20 which partake in the movements of the piston and to which the rods 21 are secured. 5 These rods connect piston 3 with an intermediate piece 22, which is rigidly attached to the guide tube 23 and carries at its back end adjustable rings 24. The guide tube 23 is slidably held in a longitudinal direction within block 13 and carries 10 the core plates 25 to which the cores 26 are attached. These according to Fig. 1 are extended into the die casting. It is easily seen from the drawing that the movements of the piston 3 are transmitted by means of the rods 21, the intermediate piece 22 and the guide tube 23 to the cores. These latter participate therefore in all the movements of piston 3.

Block 13 carries also two hollow rods 28 having checks 29 and being guided alongside of cylinder 2 in the same framing. These rods support an expelling frame 30 and carry inner rods 31 provided at their hind ends with threads and with nuts 32, by which by means of clamps 33 the expelling plates carrying the expellers 38 are attached to the expelling frame 30. Said hollow rods 28 are always kept in a determined position in relation to block 13 by means of a spring 34 cooperating with checks 35, 36. If however the checks which are adjustably held by the hollow 30 rods 28 contact with the frame, block 13 will be able to execute a movement relatively to the rods 28. At this moment also the expellers 38 will become effective which are fast to the expelling plate. The represented machine is operated as follows:

In the position shown in Fig. 1 the casting operation has been done. In space 19 of the closing cylinders 1 still remains liquid under a very high pressure. Piston 3 is maintained in its 40 position on the left. Head 39 by means of cylinder 12 has taken along block 13 when the mould was closed and has pressed block 13 together with core plate, expelling plate and movable half of the mould to the left. The movement has 45 been arrested by the stationary half of the mould and the metal flows now from the crucible 5 into the free space left between the two halves of the mould. The cylinder portions 15 and 17 are filled with liquid of constant pressure. Their 50 common effect however is not able to compensate the effect of the pressure inside space 19.

Also into the cylinders 6, 6' pressure liquid has been introduced. After the closing of the form has been completed however, a valve in this admission conduit will be closed so that the enclosed liquid volume cannot escape.

Now the opening of the mould begins, also the separating of the two mould halves, the withdrawing of the cores and the expelling of the 60

ready casting. To this end at first the pressure in space 19 is relieved by permitting the draining of the liquid therein enclosed. At this moment the constant liquid pressure in space 15 and in space 17 becomes effective. The useful piston area in space 17 is considerably larger than the area in space 15 and thus piston 3 will move to the right. The liquid enclosed within space 15 plays for at present the roll of a hydraulic coupling, so that cylinder 12 and the block 13 coupled therewith follow the movements of the piston 3. All devices carried by the block follow with it until the eyes 11, 11' of the block make contact with the checks 9, 9'.

15 At the same time the checks 29 on the hollow rods 28 are stopped by the frame 1. This position is shown in Fig. 2.

From the latter it is seen that the liquid cushions inside cylinder 6, 6' having stopped the rods 28, 28' have rendered the checks 9, 9' efficacious. Block 13 cannot advance further but the pressure in chamber 17 continues and remains further effective and prevails over the pressure in chamber 15. The liquid in this chamber returns 25 through the bore into chamber 11 and thus a relative movement has taken place between piston head 39 and cylinder 12. This movement is transmitted through rods 21 to the guide tube 23 and to the core plates 25 with cores 26. The latter are withdrawn and at this moment the adjustable rings become adjacent to cylinder 12.

Then the drain of the liquid cushion within cylinders 6, 6' will be permitted, so that the liquid pressure in chamber 17 produces a further movement of piston 3. This movement is transmitted by rings 24 to block 13. But, because the checks 29 remain already at the end of the first movement upon the frame, every movement of the block will produce a relative movement between the expelling frame 30 and expellers 38 at the end of the rods 28 and the movable half of the mould held by the block.

In Fig. 3 the position of the different machine parts at the end of this movement is shown.

45 Then the ready casting will be expelled from the mould and dropped into a container. After this a high liquid pressure is again produced in chamber 19. Piston 3 will move to the left, liberates the different checks, permits the release of spring 34 and likewise the refilling of the liquid cushions within cylinders 6, 6'. The movable half of the mould comes again into contact with the stationary half and a new casting may be operated.

55 If large cores have to be withdrawn the liquid in chamber 15 must be pressed out and then the communication between this chamber and chamber 17 will be interrupted by closing the stop valve 18. Thereby it has been attained that in 60 chamber 15 no pressure is present to resist the pressure in chamber 17 and thus the whole pressure in chamber 11 will be available for the withdrawal of the cores. The connection between piston 3 and block 13 and therefore the moving of the latter towards the checks 9, 9' is no more effected with large cores by the hydraulic coupling 15, but simply with the power by which the casting sticks to the core. This power is with large cores so considerable that it suffices 65 for opening the mould and to withdraw the block unto the checks 9, 9' whereupon the cores will be withdrawn with all the pressure of chamber 17.

70 From the above it may be seen, that the machine comprises a hydraulic coupling between

mould carrier and piston as well as also hydraulically controlled means used when the cores have to be withdrawn. By using these particular devices a much higher number of casting operations than with any other known machines are possible. The coupling and uncoupling and the operating of the checks requires no time in a casting operation. By this instance the present machine is above all adapted for an automatic operation. The hydraulic coupling and the hydraulic buffers represent a combination permitting the withdrawing of the cores of the mould carrier during the opening of the mould in the opening direction and to bring the cores again into their casting position without using further sources of pressure liquid than those afforded by the moving mould carrier.

What I claim is:

1. In a machine for die casting under pressure, a frame, a mould comprising a stationary and a movable half, a slidably arranged block carrying said movable half, a first cylinder secured to the frame and containing a hydraulically operated piston for closing and opening the mould, a piston-rod attached to said piston, a second piston secured to said piston-rod, a core plate rigidly connected with said piston-rod with the help of suitable connecting-means, a second cylinder secured to said block and containing said second piston, a pressure medium in said second cylinder and on one side of said second piston, a conduit for permitting the volume of said pressure medium to be increased and diminished, thus allowing a relative movement between said core plate and said block. 35

2. In a machine for die-casting under pressure according to claim 1, said conduit formed as a bore in said piston-rod and connecting the one portion of the first cylinder with that portion of the second cylinder, which contains the pressure 40 medium, and checks connected by suitable means with the frame and adapted to stop the block, whereby, after said stopping, the relative movement between block and core plate can begin.

3. In a machine for die-casting under pressure 45 according to claim 1, a valve in said conduit, adapted to cut off the inflow of the pressure medium into the second cylinder.

4. In a machine for die-casting under pressure according to claim 1, said conduit formed as a bore in said piston-rod and connecting the one portion of the first cylinder with that portion of the second cylinder which contains the pressure medium, a valve in said bore, adapted to cut off the inflow of the pressure medium into the second cylinder, and checks connected by suitable means with the frame and adapted to stop the block, whereby, after said stopping, the relative movement between block and core plate can begin. 60

5. In a machine for die-casting under pressure according to claim 1, further cylinders mounted on the frame and containing hydraulically operated pistons, piston-rods secured to said pistons, checks on said piston-rods, adapted to stop the block, an ejecting-device elastically connected with said block, further checks connected with said ejecting-device and adapted to bear against the frame, thus permitting of a relative movement between block and ejecting-device, and other checks on said piston-rods adapted to stop the relative movement between block and ejecting device. 65
